F. J. PRUE.

UNDERGARMENT.

APPLICATION FILED AUG. 29, 1919.

Patented Jan. 25, 1921.

UNITED STATES PATENT OFFICE.

FRANK J. PRUE, OF WOONSOCKET, RHODE ISLAND.

UNDERGARMENT.

1,366,492.

Specification of Letters Patent. Patented Jan. 25, 1921.

Application filed August 29, 1919. Serial No. 320,675.

To all whom it may concern:

Be it known that I, FRANK J. PRUE, a citizen of the United States, residing at Woonsocket, in the county of Providence 5 and State of Rhode Island, have invented a new and useful Undergarment, of which the following is a specification.

This invention relates to an undergarment of the one-piece type; the principal 10 objects, thereof, are to provide a construction which can be made of the usual tubular goods and will be so constructed that it will dispense with the excessive number of buttons, which are characteristic of the ordinary union-suit, and replace the same by a 15 single fastening device located most conveniently, and so arranged with respect to the rest of the garment that the wearer simply steps into it in putting it on in the same way 20 as is usual in putting on a pair of trousers, and then brings the two edges together at the back of the neck and fastens them there in one place only; to provide a construction 25 to hold the entire garment in place effectively and without permitting of any openings through the garment in the vicinity of the fastening device; to provide a construction in which the front or chest portion shall be undivided and can be modified 30 by the addition of another thickness if desired so as to furnish a more efficient protector for the chest and abdomen if desired; and to provide an arrangement by which 35 the space across the front between the arm holes, shall be shorter than that across the back between the arm holes, so that the garment will fit comfortably at these points and give full play to the arms.

Other objects and advantages of this 40 invention will appear hereinafter.

Reference is to be had to the accompanying drawings, in which—

Figure 1 is a front view of a one-piece under garment constructed in accordance 45 with this invention;

Fig. 2 is a rear view of the same;

Fig. 3 is a front view of a modification;

Fig. 4 is a fragmentary sectional view on the line 4—4 in Figs. 1 and 3 of the front 50 of the garment.

The garment preferably is made from tubular goods as is well understood in this art, although that is not necessary. The lower part needs no special description as 55 the main portion and both legs are continuous with the top part. There is a hori-

zontal seam 10 below the waist line between them for attaching the top of the front flap 11 and inner flap not shown. The usual opening in front is formed by these 60 flaps. The front flap is bounded by a seam 12.

On the rear, is a seam 13 extending upwardly from the inner side of the left leg to a horizontal seam 14 at or above the 65 waist line. The opening at the front extends through to and is bounded by a flap 15 which terminates at the seam 14 and the flap 16 underneath is similarly connected with the above-mentioned inner flap as is 70 well understood in this art.

At the top of the flap 15, which is sewed down at this point by the seam 14 to the thickness underneath, another flap 17—19 extends upwardly outside. This is sewed 75 down at the line 14 and is free from there to the top. This flap is shown as made in two pieces, but can be made in any desired way. It is to be noted that the back 18 which extends under this flap 17—19 is sewed to it 80 for a considerable distance horizontally along the seam 14 and terminates along a vertical central seam to which a triangular flap is secured extending to an edge 26, well under the flap 19 when the garment is on 85 the person and buttoned up. This provides a wide overlap for the two parts 17 and 18. The rear flaps at the top start on either side at the hip or waistline and overlap sufficiently so that when fastened at the top, a 90 single fastening will keep them fully closed. These flaps are connected together along the horizontal line below. At the top they are connected together by a fastening device of any desired kind but shown as in the form 95 of a button 20 and buttonhole and this is the only fastening device on the garment.

This device permits of the making of the front or chest of the garment entirely without seams as shown at 21 in Fig. 1. I have 100 shown in this figure a double thickness terminated by a seam 22 for the upper part of the chest.

It is to be observed that the distance between the armholes 23 across the chest is 105 shorter than the distance between them across the back. This can be provided for conveniently as shown, by cutting each armhole at the back substantially straight up from the bottom of the armhole and cutting 110 it on a concave curve at the front. This is feasible on account of the continuous chest

21 and the widely overlapping flaps on the back, and permits of the free use of the arms without binding or wrinkling. In other words, without introducing too much 5 fullness across the front.

In the form shown in Fig. 3, the only modification is that the reinforcing inner chest piece 24 extends clear down below the 10 waist line to the seam 25 and we then have a double protecting member, not only for the chest, as in Fig. 1, but also for the abdomen.

In the use of the device, all the wearer 15 has to do is to open the suit at the back by means of the fastening at 20 and to step into the suit, pull it up, insert the arms into the 20 openings 23 or sleeves if they are used, and then fasten it at the back at 20 in one place only. This is a very simple operation compared with that that would be required to 25 button it if it were buttoned up in front. Furthermore, all openings in the front are dispensed with, thus making the front, even in the form with one thickness only, a real chest protector.

By arranging the seams between the main 30 parts of the back and the two parts 19 and 17 of the overlapping flap so that the tops and bottoms of said seams will register, it 35 will be obvious that the pull due to wearing the garment, and especially any pull due to the wearer's bending over, will be transmitted along these seams and applied at the same point. As these seams are practically vertical such a pull will have no real tendency to open the garment at the back either above the seam 14 or below it.

Although I have illustrated and described

only two forms of my invention, I am aware 40 of the fact that many modifications can be made therein without departing from the scope thereof, as expressed in the claim. Therefore I do not wish to be limited to all the details herein shown and described, but what I do claim is:—

As an article of manufacture a one-piece undergarment having a continuous front or chest portion without openings therein and having an opening in the back bounded by overlapping front and rear flaps both continuous and integral all the way from the neck to the crotch, a single fastening device therefor at the top of said flaps in the back above, the outer and inner overlapping flaps extending from said fastening device at the 55 top down to the crotch in the back and under the crotch where they overlap, and having two continuous seams by which said flaps are secured to the main body of the garment, said seams extending from the 60 fastening device at the top to the crotch in the back in a substantially central vertical line and substantially registering with each other at the top of the back and at a point 65 near the crotch, and having a horizontal seam extending substantially all the way across the back near the waistline, said seam throughout substantially one-half of its length securing one of said flaps to the outside of the back of the main body of the 70 garment, and the other half of said seam securing the other of said flaps to the inside of the back of the main body.

In testimony whereof I have hereunto affixed my signature.

FRANK J. PRUE.
